UNITED STATES PATENT OFFICE

JOHN F. O'CONNOR, OF CHICAGO, ILLINOIS, ASSIGNOR TO W. H. MINER, INC., OF CHICAGO, ILLINOIS, A CORPORATION OF DELAWARE

CAR CONSTRUCTION

Application filed April 9, 1928. Serial No. 268,561.

This invention relates to improvements in car construction.

One object of the invention is to provide a simple, efficient and reliable means for connecting the body bolster and arch or transom member of a railway car, including a center or king pin headed at one end and extending through the body bolster and arch member, wherein readily detachable means is employed at the end of the pin to secure the same against detachment, comprising a separable, sectional head portion.

A further object of the invention is to provide a retaining means of the character indicated, for a center pin of a railway car, having a fixed head at one end and a detachable head secured to the other end, the detachable head and pin having co-operating locking abutment shoulders.

Another object of the invention is to provide means for connecting the arch or transom member to the bolsters of railway car trucks, presenting relatively large bearing areas to provide a rugged and reliable construction, wherein the connecting means includes heavy trunnion members and co-operating bearing sections on the truck bolsters and transom member, respectively, together with cup-shaped locking elements engaging over said trunnions and bearing members to secure the same together.

In the drawing, forming a part of this specification, Figure 1 is a plan view of a portion of one of the body bolsters and a portion of the car truck structure of a railway car, illustrating my improvements in connection therewith. Figure 2 is a longitudinal, vertical, sectional view, corresponding substantially to the line 2-2 of Figure 1. Figure 3 is a vertical, sectional view, corresponding to the line 3-3 of Figure 2. And Figure 4 is a bottom plan view of the structure at the central portion of the transom or arch member of the car truck.

In said drawing, 10 designates one of the body bolsters of a railway car underframe structure, which is supported by an arch or transom member 11 of the car truck, the arch member 11 being in the form of a spider and having oppositely projecting pairs of sub-

stantially radially arranged arms 12-12, the pairs of arms 12 extending respectively forwardly and rearwardly from the body bolster 10. The railway car truck includes the usual truck bolsters 13-13 which, as shown, are spaced apart and support the transom member. The body bolster 10 is provided with the usual center bearing section 14 which includes a vertically disposed sleeve-like section connecting the top and bottom members of the body bolster proper. At the center bearing section, the lower member of the body bolster is provided with the center bearing member proper 15, the same being in the form of a downwardly projecting enlargement having a spherical bearing surface 16. The center bearing member proper is recessed at the center, as indicated at 17, to receive the co-operating portion of the complementary bearing member on the transom 11.

The transom member 11 has the upper section thereof formed with an upstanding enlargement 18 which has a spherical top bearing surface 19 mating with the bearing surface 16 of the body bolster. The bearing member of the transom is provided with a central, frusto-conical projection extending into the opening 17 of the bearing member of the body bolster. The top and bottom sections of the transom member are connected by an integral sleeve-like section 119, which is adapted to receive the center or king pin. The sleeve-like sections 14 and 119 of the body bolster and transom member provide aligned openings, adapted to accommodate the center or king pin which connects the bolster to the transom. As shown, the pin receiving openings are preferably centrally enlarged. The pin receiving opening of the body bolster is enlarged at the upper end, thereby providing a seat 20 for the head of the center pin. At the bottom of the transom member a pocket 21 is provided, which is in alignment with the pin receiving opening of the transom. As shown, the pocket is of the same width as the pin receiving opening, but is elongated in opposite directions, as shown, for a purpose hereinafter pointed out.

In carrying out my invention, I provide the truck bolsters 13 with bearing means

which supports the outer ends of the arms of the transom member. As shown, each truck bolster 13 has two upstanding bracket members 22 which are provided with horizontally disposed trunnion members 23. Each trunnion member, as shown, extends laterally beyond the base portion of the bracket 22. The extremities of the arms 12 of the transom member are provided with semi-cylindrical bearing portions 24 which engage over the upper portions of the trunnions 23.

It will thus be evident that the extremities of the arms 12 of the transom are directly supported by the bearing sections 24 thereof on the trunnion members 23.

In order to retain the parts in position, a pair of retaining caps 25—25 are employed, each cap being in the form of a disc-like member provided with an annular flange 26. The annular flange 26 of each cap has the lower portion thereof inwardly offset, as indicated at 27, so as to fit the trunnion member 23, the remaining portion of the flange 26 thereof fitting over the bearing section 24 of the corresponding arm 12 of the transom 11. As most clearly shown in Figure 3, the flanges of the caps 25 are of such a width that they contact with the bracket member 22 as the parts are assembled. The two caps 25 of each connecting member are engaged over the opposite projecting ends of the corresponding trunnion 23 and over the ends of the bearing section 24 which co-operates with said trunnion. It will be clear that when the parts have been thus assembled, the bearing section 24 is held to the corresponding trunnion 23. Removal of the caps 25 is prevented by a bolt 37 which extends through aligned openings in the two caps and the trunnion member 23.

My improvements are herein illustrated as employed in connection with a railway car truck of the six-wheel type, the central axle of the truck being designated by 28, as illustrated in Figure 2.

My improved means for connecting the body bolster and the transom member of the car truck comprises a king or center pin A and a retaining member proper B.

The king pin A is of the headed type, having the head member 29 at the upper end thereof and formed integrally therewith. The pin is of such a length as to extend entirely through the openings in the body bolster and the arch member, with the lower section thereof, which is designated by 30, extending into the pocket 21 and protruding beyond the bottom of the transom member. The section 30 of the pin is provided with an annular groove 31 adjacent the lower end thereof, thereby providing a head member 32 at the lower extremity of the pin which is of the same diameter as the body portion proper of the pin. The top wall of the annular groove 31 is preferably flush with the

top wall of the pocket 21, as most clearly illustrated in Figure 2.

The retaining member B comprises two complementary blocks which together form a sectional, detachable head for the lower end of the pin. Each of the blocks B is centrally cut away, as indicated at 33, to fit the corresponding side of the lower end of the pin, the cut away portions of the blocks being of two diameters, as shown, so as to provide a step arrangement which fits both the head 32 and the groove portion 31 of the section 30 of the pin. In other words, each block is provided with an enlarged recess which fits the head 32, and an inturned flange-like section above said recess, which engages within the annular groove 31. When the detachable sectional head is assembled with the pin, the sections embrace the opposite sides of the pin and, in effect, form a continuous head member. The sections are retained in fixed position on the pin by means of a transverse bolt 34 extending through aligned openings in the sections of the member B and a transverse opening in the head portion 32 of the pin.

In assembling the parts when connecting the truck to the body bolster, the king pin A is inserted through the top of the body bolster and passed through the aligned pin receiving openings of the body bolster and the arch or transom member. The head 29 of the pin will thus be seated within the pocket 20 at the top of the body bolster, thereby preventing downward movement of the pin A. The sectional retaining head B is then applied to the lower end section 30 of the pin by inserting the two sections at opposite sides of the pocket 21, bringing the inturned flange sections thereof into alignment with the groove 31. The two sections of the head B are then moved laterally in the pocket 21 engaging the flange sections thereof within the groove 31 of the pin. After the head has been thus applied, the same is secured by the bolt 34. As will be evident, when the parts have been thus assembled separation of the truck member from the body bolster is positively prevented due to the engagement of the head 29 at the upper end of the pin with the abutment surface of the body bolster and engagement of the sectional head B at the lower end of the pin with the top wall of the pocket 21 of the transom member.

From the preceding description, taken in connection with the drawing, it will be evident that I have provided a simple and reliable retaining means for locking the king or center pin of a body bolster and truck connection so that separation of the body bolster and truck member is positively prevented thereby greatly reducing the danger of accidents to railway equipment due to the separation of these parts.

It will also be noted that by providing the

5 trunnion members on the bolsters of the truck, over which the bearing portions of the arch member engage, a very durable and rugged construction of support for the arch member of the truck is provided, thereby adding greatly to the life of the car truck structure, inasmuch as the retaining pins or bolts which connect the arch member to the truck bolsters are relieved from strains and shearing action.

10 While I have herein shown and described what I consider the preferred manner of carrying out my invention, the same is merely illustrative and I contemplate all changes and modifications which come within the scope 15 of the claims appended hereto.

I claim:

1. In a swiveled connection of a body bolster and truck of a railway car, wherein the truck includes a transom member supporting 20 the body bolster, the combination with a center pin extending through the body bolster and transom member, said pin having a fixed head at one end; and a detachable sectional head member secured to the other end of the 25 pin, said pin and sectional head having a tongue and groove connection; and means extending through said sections to secure the same together and maintain said tongue and groove connection interengaged.

30 2. A king pin for uniting the truck of a railway car to the body bolster thereof, said pin being headed at opposite ends, one of said heads being fixed and the other head being detachable, said detachable head comprising separable sections embracing the pin proper, said sections and pin having interengaging flange and groove connection.

35 3. In a railway car construction, the combination with a body bolster member; of a truck 40 provided with a transom member on which the body bolster member is swiveled; a king pin extending through said members, said pin having a head at the upper end, co-operating with abutment means on the body bolster, the 45 lower end of said pin being grooved; a detachable, sectional head member on the lower end of the pin co-operating with abutment means on the transom member, the sections of said head embracing the pin and having 50 inturned flanges seated in said groove; and means for securing the sections of said head together.

4. In a railway car construction, the combination with a body bolster member; of a truck 55 provided with a transom member supporting said bolster, said body bolster being swiveled on the transom member, said members having aligned center pin receiving openings, the outer end portion of one of said 60 openings being laterally enlarged; a center pin accommodated in said openings, said center pin having a section thereof extending through said laterally enlarged portion of the opening, said last-named section of the 65 pin being provided with a groove; a detach-

able cylindrical head secured to said last-named section, said head comprising a pair of complementary block members recessed on the inner sides to conform to said pin and provided with inturned flange sections seated 70 in said groove; and means for securing said blocks together, said blocks being accommodated in said laterally enlarged section of the recess when the parts are being assembled and being laterally displaceable toward each 75 other in said recess to permit engagement of the flanges thereof with the groove of the pin.

5. In a railway car construction, the combination with a body bolster; of a car truck including a transom member on which the 80 body bolster is swiveled, said body bolster and transom member being provided with aligned center pin receiving openings, said opening of the body bolster being enlarged at the upper end to accommodate the head of 85 the center pin and the opening of the transom being enlarged at the lower end to accommodate a locking element; a center pin extending through said openings, said pin being headed at the upper end and cut away adjacent the opposite end to provide a head member of not greater diameter than the pin proper; and a detachable retaining element accommodated in the enlarged portion 90 of the opening of the transom, said retaining member comprising a pair of blocks embracing and fitting the head at the lower end of the pin, said blocks having flange sections extending into said cut away portion of the pin and engaging in back of said head.

6. In a railway car construction, the combination with a body bolster; of a truck member including spaced truck bolsters and a transom member on which the body bolster is swiveled, said truck bolster being provided 105 with trunnion members for supporting the transom and the transom being provided with bearing portions engaging over the trunnion members; retaining means co-operating with each trunnion, comprising cup-shape flanged 110 disc members having the flanges thereof engaging over the opposite ends of said trunnion and the bearing portions of the corresponding arm of the transom member; and a retaining bolt securing said retaining members to the corresponding trunnion.

In witness that I claim the foregoing I have hereunto subscribed my name this 6th day of April, 1928.

JOHN F. O'CONNOR. 120
